ELECTRICAL SWITCH

William P. Gallagher and Carl Weber, Chicago,
Ill., assignors to International Register Com-
pany, Chicago, Ill., a corporation of Illinois

Original application October 6, 1947, Serial No.
778,104. Divided and this application April 8,
1949, Serial No. 86,324

14 Claims. (Cl. 200—153)

1

The present invention relates to electrical switches of general utility type, such as may be used for controlling 110 or 220 volt heating, lighting or power circuits.

The present application is divisional of our copending application, Serial No. 778,104, filed October 6, 1947, which is directed primarily to an improved automatic timing mechanism for controlling the heating circuits of electric stoves, electrical ovens and the like. In that earlier application, we disclosed the present electrical switch as being responsive to the automatic timing controls for closing and opening the heating circuit of the stove at preselected times. While the present electrical switch was devised particularly for use in that automatic timing mechanism, and functions very satisfactorily in that mechanism, the switch is not limited to such use.

One of the objects of the invention is to provide a simple, inexpensive electrical switch which will produce a relatively large, quick-opening movement of the switch contacts in response to a relatively small range of movement of the switch actuator. In the above mentioned automatic timer for electric stoves and the like, the actuating motion is imparted or translated from the timing controls to the switch assemblies through a multiple step rotating cam. Our improved switch is uniquely adapted to this cam type of operation, but is not necessarily limited thereto.

Another object of the invention is to provide a utility switch of the above general type which is extremely simple and inexpensive to assemble. In arriving at a low cost of production, the item of cost of assembly can be just as important, or more important, than cost of materials, or cost of fabrication into switch parts. Our improved construction of switch can be quickly and easily assembled into a complete, self-contained unit which can be stocked as such, and thereafter assembled in the general assembly with the automatic timing mechanism.

Other objects, features and advantages of the invention will appear from the following detailed description of one preferred embodiment thereof. In the accompanying drawing illustrating such embodiment:

Figure 1 is a fragmentary plan view illustrating our improved switch on an enlarged scale, and showing the switch actuating cam in dotted lines;

Figure 2 is a longitudinal, sectional view through the switch assembly, taken approximately on the plane of the line 2—2 of Figure 1;

2

Figure 3 is a detail, sectional view taken horizontally on the plane of the line 3—3 of Figure 2;

Figure 4 is a detail, sectional view taken vertically on the plane of the line 4—4 of Figure 3;

Figure 5 is a fragmentary, detail view corresponding to a section taken approximately on the plane of the line 5—5 of Figure 2;

Figure 6 is a fragmentary, plan view illustrating the actuating cam in greater detail; and

Figure 7 is a fragmentary, detail view of a modified construction of switch blade.

The switch is assembled upon a base plate 118 composed of any suitable insulating material.

In accordance with the disclosure in our prior application, Serial No. 778,104, we have shown the switch as being actuated by a rotatable or oscillatable cam 122 mounted upon a switch actuating shaft 111. This cam is shown as having

four switch actuating positions formed in its periphery, viz. a cam valley 154 for closing the switch, a cam hump 155 for opening the switch, a cam valley 156 for closing the switch, and a cam hump 157 for opening the switch. Riding

on these cam formations is a cam following pin 159 which projects laterally from the end of a switch actuating plate or slide bar 161. It will

be understood that other operating mechanisms may be employed for actuating the switch. For example, any appropriate operating instrumentality can be employed which will impart motion to the pin 159 comparable to that imparted by the cam 122.

The switch actuating plate or slide bar 161 is composed of insulating material, such as

“Bakelite,” and is mounted for endwise reciprocating motion parallel to the surface of the base plate 118, but spaced slightly therefrom. The switch actuating shaft 111 passes down through a longitudinal slot 162 in the plate or slide bar 161, and establishes a point of guidance for guiding

the to and fro motion of the plate 161. Referring to Figure 2, the lower end of the shaft 111 has a reduced portion 116 which is seated

in a bearing ferrule 117 set into the insulating base plate 118 of the electric switch. The shaft

can rotate in this bearing ferrule 117, and in the aforementioned adaptation to an automatic timing mechanism the shaft could tilt slightly in this bearing ferrule. This ferrule comprises an

upper tubular portion 117a extending upwardly through the guide slot 162 in the slide plate 161, and comprises a downwardly extending tubular portion 117b which is crimped over on the under

side of the mounting plate 118. Intermediate

these tubular portions, the ferrule is formed with

50

55

Figure 1 is a fragmentary plan view illustrating our improved switch on an enlarged scale, and showing the switch actuating cam in dotted lines;

a boss portion 117c, and with a retaining flange 117d projecting from the upper portion thereof. The boss portion bears against the top of the base plate 118, and the annular retaining flange guides or confines the yoke to which the tension springs are connected, as will be later described.

The slide plate 161 has T-shaped cross arms 163 projecting outwardly to the sides and overlying the movable switch blades. These switch blades, designated 164, are of angular or substantially L-shaped formation carrying movable contacts 165 on the inward sides of their outwardly diverging ends 164a. These movable contacts 165 are adapted to engage with stationary contacts 166 carried by stationary terminals 167 secured to the insulating base plate of the switch. The switch blades are adapted to have rocking movement about the outer corners 168' of terminal blocks 168. The inside corner angle 171 at the angle bend of each blade has rocking movement on such shoulder edge 168' of its companion terminal block 168. Current is conducted to the movable switch blade through this terminal block 168 and through this rocking edge contact established at 168'—171. The inwardly bent arms 164b of the blades bear against humps 172 projecting from the cross arms 163. When the switch actuating plate or slide bar 161 is shifted to the right, motion is transmitted through the humps 172 to the inwardly extending arms 164b of the switch blades for rocking the blades to open circuit positions.

Tongues 174 punched inwardly from the outer arms 164a of the switch blades serve as attachment hooks to which the outer ends of tension springs 175 are connected. These tongues also function as guiding and retaining elements for the switch blades by extending into U-shaped guide spaces 176 formed in the outer surfaces of the terminal blocks 168, as shown in Figures 3 and 4. Similar U-shaped guideways 178 are formed in the inner sides or edges of the terminal blocks 168 for receiving guide wings 179 projecting from the plate 161. This arrangement establishes lateral guidance for the left hand end of the plate 161. The inner ends of the tension springs 175 are hooked to hook ends on an insulating yoke 181 which has rockable bearing contact against the boss portion 117c under the confining flange 117d of the bushing or ferrule 117. The tension springs 175 perform the two-fold function of normally holding the movable switch contacts 165 pressed firmly against the stationary switch contacts 166, and also of holding the corner angles 171 of the switch blades pressed firmly against the corner edges 168' of the terminal blocks 168 for effective current conduction through these lines of rocking contacts. The T-shaped cross arms 163 of the switch actuating slide plate 161 are formed with downwardly turned sloping ends 163' which perform the two-fold function of stop members for limiting the outward swinging movement of the current conducting legs 164a of the switch blades, as indicated in dotted lines, and which also serve as confining members for preventing accidental outward displacement of the switch blades to the point where the tongues 174 might slip out of the guide spaces 176. A neutral terminal block 185 may also be secured to the base plate 118, as for example, at a point beyond the cross arm portion 163 of the slide plate. The pivot terminal blocks 168, contact terminal blocks 167 and neutral terminal blocks 185 have rectangularly shaped anchoring portions which extend down through

rectangular openings in the base plate 118 and are headed or crimped over on the under side thereof, as indicated at 187 in Figure 4. Threaded bores 188 extend upwardly through each of these terminal blocks for receiving terminal screws adapted to be inserted into the terminal blocks from the back side of the base plate 118 for connecting conductors to these terminal blocks. The construction illustrated affords a single throw, double pole switch, but it will be understood that the invention might also be embodied in a single throw, single pole switch, or even in a double throw switch.

In the embodiment shown in Figures 1 and 3, the tongues 174 are punched out of the switch blades with the free ends of the tongues pointing toward the switch actuating legs 164b of the switch blades. In the alternative construction illustrated in Figure 7, this is reversed so that the free end of the tongue 174 is bent inwardly toward the current conducting leg 164a of the switch blade.

With regard to the assembly of this improved switch, it will be seen that no screws, rivets, or other fastening devices are necessary for holding the switch plate 161, switch blades 164, springs 175, or yoke 181 in assembled relation. One simplified method of assembling these parts is to place the yoke 181 under the retaining flange 117d, connect the spring 175 from this yoke to the tongues 174 of the switch blades, and then temporarily place the switch blades in outwardly disposed positions, with the actuating arms 164b bearing on the rocker edges 168', and spaced outwardly sufficiently to permit the guide wings 179 to pass therebetween. Thereupon, the switch actuating plate 161 is slid inwardly from the left so as to have the guide wings 171 move into the guide ways 178 in the pivot terminal blocks 168. Thereafter, the switch blades 164 are shifted inwardly to their proper positions and the guide slot 162 is dropped down over the ferrule shank 117a, thereby preventing lateral displacement of the switch plate to the left. This practically completes the assembly of the switch; the actuating cam 122 can be included in the assembly at this time, or at a later stage when the assembled switch is included in the timing mechanism.

While we have illustrated and described what we regard to be the preferred embodiment of our invention, nevertheless it will be understood that such is merely exemplary and that numerous modifications and rearrangements may be made therein without departing from the essence of the invention.

We claim:

1. In an electric switch, the combination of a T-shaped actuating plate of insulating material, means mounting said plate for endwise reciprocation, a rotary actuating member, follower means responsive to said actuating member for reciprocating said plate, a pair of movable contact blades, one to each side of said actuating plate, said blades comprising bars having inwardly extending actuating ends and angularly extending contact ends, movable contacts carried by said angularly extending contact ends, stationary contacts cooperating with said movable contacts, stationary supports on which said contact blades have rocker mounting, actuating surfaces on said T-shaped actuating plate adapted to engage said actuating ends of said blades and to cause rocking movement of said blades, and spring means connected with said blades tending to oppose such latter movement.

2. In an electric switch, the combination of a switch blade, a pivot terminal therefor, said blade comprising two angularly extending portions defining an inside corner angle therebetween, said inside corner angle having rockable pivoting engagement against said pivot terminal, a movable contact carried by one of said angularly extending portions of said switch blade, a stationary contact adapted to be engaged by said movable contact, spring means normally holding said contacts closed, and a slide bar switch actuator adapted to press against the other of said angularly extending portions in a direction toward said pivot terminal for actuating said switch blade through the other of said angularly extending portions.

3. In a switch, the combination of a switch blade, a pivot terminal therefor having a fulcrum edge, said blade being substantially L-shaped comprising two angularly extending portions defining an inside corner angle therebetween, said inside corner angle having rockable pivot mounting against said fulcrum edge of the pivot terminal, a movable contact carried by one of said angularly extending portions of said switch blade, a stationary contact adapted to be engaged by said movable contact, spring means holding said inside corner angle pressed against said fulcrum edge and also normally holding said contacts closed, said inside corner angle and fulcrum edge establishing a current conducting path between said pivot terminal and said switch blade, and a slide bar type of actuating means operative to apply pressure to the other of said angularly extending portions for actuating said switch blade to open circuit position.

4. In a switch, the combination of a switch blade, a pivot terminal therefor comprising a fulcrum edge, said blade being substantially L-shaped comprising two angularly extending portions defining an inside corner angle therebetween, said inside corner angle having rockable pivoting engagement against said fulcrum edge, a movable contact carried by one of the angularly extending portions of said switch blade, a stationary contact adapted to be engaged by said movable contact, spring means holding said inside corner angle pressed against said fulcrum edge, said inside corner angle and fulcrum edge establishing a current conducting path between said switch blade and said pivot terminal, and actuating means operative to apply pressure to the other of said angularly extending portions for actuating said switch blade.

5. In a switch, the combination of a switch blade, a fulcrum terminal therefor comprising a fulcrum edge, said blade comprising a current conducting arm and a switch actuating arm extending at an angle to each other to define a corner angle therebetween, the inner surface of said corner angle having rockable engagement against the fulcrum edge of said fulcrum terminal, a movable contact carried by said current conducting arm, a stationary contact adapted to be engaged by said movable contact, and reciprocable switch actuating means operable to transmit a reciprocable switch actuating motion to said actuating arm, said reciprocable switch actuating means comprising stop means for limiting the outward swinging movement of said current conducting arm.

6. In a switch, the combination of a switch actuating slide bar having a pair of laterally extending arms, a pair of switch assemblies actuated by said pair of arms, each of said switch

10
15

assemblies comprising a switch blade, a fulcrum terminal therefor having a fulcrum edge, said blade comprising two angularly extending portions defining a corner angle therebetween; said corner angle having rockable fulcrum engagement against the fulcrum edge of said terminal, a movable contact carried by said switch blade, a stationary contact adapted to be engaged with said movable contact, said pair of laterally extending arms on said switch actuating slide bar being arranged to transmit switch opening motion to said pair of blades, and tension springs connected with said pair of switch blades serving to hold said contacts closed, said blades pulled into fulcrum engagement against said fulcrum edges, and said slide bar shifted to one position.

7. In a switch, the combination of a T-shaped switch actuating plate mounted for endwise shifting movement, a pair of substantially L-shaped switch blades adjacent the sides of said plate and arranged to be actuated by the cross arms of said T-shaped plate, a fulcrum terminal for each switch blade, each blade comprising an inside angle portion adapted to have rockable fulcrum engagement against said fulcrum terminal, the cross arms of said T-shaped plate exerting switch actuating pressure against said blades in a direction to hold said inside angle portion pressed against said fulcrum terminal and contacts controlled by said switch blades.

8. In a switch, the combination of a pair of substantially L-shaped switch blades having movable contact portions, stationary contacts adapted to be engaged by said movable contact portions, a pair of pivot terminals for said switch blades, said switch blades having pivot mounting on said pivot terminals at the inside angle of their substantially L-shaped formation, and a T-shaped switch actuator mounted for reciprocatory movement between said switch blades and having its cross arms arranged to actuate said switch blades by exerting pressure against said blades in a direction toward said pivot terminals.

9. In a switch, the combination of a pair of substantially L-shaped switch blades having movable contact portions, stationary contacts adapted to be engaged by said movable contact portions, a pair of pivot terminals for said switch blades, the inside angle of said substantially L-shaped switch blades having rockable pivot bearing against said pivot terminals, a T-shaped switch actuating plate mounted for reciprocatory movement between said switch blades and having its cross arms arranged to actuate said switch blades, a yoke mounted under said switch actuating plate, and springs operatively connected between said yoke and said switch blades tending to move said switch blades to closed position.

10. In a switch, the combination of a pair of switch blades having movable contacts, stationary contacts adapted to be engaged by said movable contacts, a pair of pivot terminals for said switch blades, each of said blades comprising a current conducting arm and a switch actuating arm extending at an angle to each other to define a corner angle therebetween, said corner angle having rockable engagement against said pivot terminal, and a T-shaped switch actuating plate mounted for reciprocatory movement between said switch blades, said T-shaped switch actuating plate having its cross arms arranged to transmit switch opening movement to the switch actuating arms of both blades, and having angularly projecting ends operative to engage the current

70
75

conducting arms of said blades for limiting the switch opening movement of said blades.

11. In an electric switch, the combination of a switch blade, a fulcrum terminal therefor comprising a fulcrum edge, said blade comprising a current conducting arm and a switch actuating arm extending at an angle to each other in a substantially L-shaped formation to define a corner angle therebetween, said corner angle having rockable engagement against the fulcrum edge of said fulcrum terminal, a confining slot formed in said fulcrum terminal, a confining lug projecting from said switch blade and engaging in said confining slot, and a switch actuator arranged to transmit switch actuating pressure to said switch actuating arm, said switch actuator comprising confinement means for preventing accidental disengagement of said confining lugs from said confining slots.

12. In a switch, the combination of a switch blade, a fulcrum terminal therefor comprising a fulcrum edge, said blade comprising a current conducting arm and a switch actuating arm extending at an angle to each other in a substantially L-shaped formation to define a corner angle therebetween, said corner angle having rockable engagement against the fulcrum edge of said fulcrum terminal, a movable contact carried by said current conducting arm, a stationary contact adapted to be engaged by said movable contact, a confining slot formed in said fulcrum terminal, a confining lug projecting from said switch blade and engaging in said confining slot, and spring means connected to said confining lug normally tending to hold said contacts closed.

13. In a switch, the combination of a pair of switch blades having movable switch contacts, a pair of stationary switch contacts adapted to be engaged with said movable contacts, a pair of pivot terminals for said switch blades having confining slots formed in their outer surfaces and guard slots formed in their inner surfaces, said blades having confining lugs engaging in said confining

slots, and a switch actuating slide plate having guide wings engaging in said guide slots and arranged to actuate said switch blades.

14. In a switch, the combination of a rotatable switch actuating shaft, a cam on said shaft, a cam follower responsive to said cam, a T-shaped switch actuating plate to which said cam follower is secured, said switch actuating plate having a guide slot therein through which said shaft extends, a pair of switch blades, said switch blades having movable switch contacts adapted to engage with stationary switch contacts, separate fulcrum terminals for said switch blades, each of said fulcrum terminals comprising a fulcrum edge, each of said switch blades comprising a current conducting arm and a switch actuating arm extending at an angle to each other to define a corner angle therebetween, said corner angle having rockable engagement against the fulcrum edge of said fulcrum terminal, said current conducting arm carrying said movable switch contact, the cross arms of said T-shaped switch actuating plate being arranged to transmit switch opening motion to the switch actuating arms of both switch blades, and spring means normally tending to hold said contacts closed and to hold said corner angles pressed against said fulcrum edges.
